UNITED STATES PATENT OFFICE.

JAMES T. WEST, OF ROCKINGHAM, NORTH CAROLINA.

COTTON-SEED LINTER.

1,265,014.

Specification of Letters Patent.

Patented May 7, 1918.

Application filed January 26, 1915. Serial No. 4,507.

To all whom it may concern:

Be it known that I, JAMES T. WEST, a citizen of the United States, residing at Rockingham, in the county of Richmond and State 5 of North Carolina, have invented new and useful Improvements in Cotton-Seed Linters, of which the following is a specification.

This invention relates to improvements in cotton seed linters, *i. e.*, machines interposed 10 between the gin and the delinter for thoroughly cleaning the lint from the seed issuing from the gin. The cotton product obtained from the linter is, as compared with that obtained from the delinter, composed 15 of relatively long fibers, and, if free from foreign matter, possesses substantial commercial value.

The machine which forms the subject of the present invention has certain broad features in common with the machine disclosed 20 in my prior pending application Serial Number 864,651, notably the elimination of the usual mote board and the provision of specially arranged baffles for causing whirling 25 or eddying currents of air in the lower portion of the cylinder casing, which currents are instrumental in producing the ultimate deposit, within said casing, of substantially all impurities or foreign matter.

30 The principal object of the present invention is to provide certain improvements in connection with the construction and arrangement of the baffles for producing the whirling or eddying air currents above referred to, whereby the separation of impurities, foreign matter or trash from the lint is accomplished with greater thoroughness and reliability and is substantially complete both as to the heavier particles of trash or foreign 35 matter and as to the lighter and finer particles of trash or foreign matter.

A further object of the invention is to provide an arrangement of baffles whereby the air current which issues from between 45 the brush cylinder and the gin saws will be divided into two streams, the upper of which is of greater intensity and will carry the lint and a percentage of relatively fine trash, and the lower of which is of less intensity and will, for a portion of its travel, carry the heavier trash in a direction favorable to the reliable precipitation of such heavier trash.

50 A further object of the invention is to provide an arrangement of baffles whereby two distinct air currents are produced, one

of which is utilized in the precipitation of the heavier particles of trash and the other of which, being a whirling current or eddy, is used in the precipitation of the lighter 60 particles of trash. In this way, the recovery of substantially all the trash is provided for by substantially independent air currents which are suitably differentiated from one another with regard to their special adaptability 65 for the separation, respectively, of the heavier and finer particles of trash from the lint.

A further object of the invention is to provide an arrangement of baffles whereby 70 the air current in which the heavier particles of trash are suspended first travels downwardly for a considerable distance and thereafter travels horizontally toward the flue so that the heavier particles of trash, 75 while moving with the air current as it travels downwardly, acquire sufficient downward momentum to prevent them from being carried over, in any event, with the said air current as it changes into its horizontal path 80 of travel.

In addition to the novel arrangements of baffles above referred to, the invention includes an improved means for effecting a recovery of any cotton seed which may fall 85 through the spaces between the gin saws.

The above and other novel structural features and advantages will be made apparent as the description proceeds.

An embodiment of the invention is illustrated in the accompanying drawing which consist of a longitudinal sectional view showing the construction of the improved linter and the relation of the linter and the condenser. The linter, as regards the instrumentalities for cleaning or stripping the cotton from the seed, may be of any suitable construction, the organization shown being 90 the one ordinarily employed.

The working parts are inclosed in a casing 100 1 and comprise the usual saws 2, grid 3, brush cylinder 4, float 5, division plate 6 and feed spout 7.

As usual, the saws and brush cylinder are mounted in the upper portion of the casing 105 1 and said casing is open to the atmosphere at various places, for example, in the lower portion of its rear wall, as at 8, adjacent the float 5, as at 9 and in the front wall, as at 10. The opening 10 serves as a discharge 110 mouth for the chute provided by the inclined grid 3 and those seeds which are too

large to pass between the bars of said grid and the adjoining saws issue from the casing 1 through the opening 10.

The casing 1 is connected by a flue 11 to 5 the usual condenser 12, said flue, as usual, leading from the rear side of the casing adjacent the lower side of the brush cylinder 4.

The improved baffle arrangement for producing the eddying or whirling air currents 10 in the lower portion of the cylinder casing, comprises a baffle, designated generally as 13, which projects inwardly and downwardly from the lower wall of the flue 11, a second baffle, designated generally as 14, which is arranged under the saws 2 and has a generally converging relation to the baffle 13, and a third baffle, designated generally as 15, and arranged under and adjacent 15 to the brush cylinder 4 and intermediate the baffles 13 and 14. The baffles 13 and 14 are somewhat separated at their lower ends to provide a relatively wide discharge space 20 16 through which the heavier particles of 25 trash separated from the lint within the casing 1 are precipitated upon the floor of said casing.

The baffle 15 has a substantially vertical arrangement and is preferably of relatively 30 short length, *i. e.*, shorter than the baffles 13 and 14, its function being to divide the downward air current induced by the rotation of the brush cylinder and the saws and issuing from between said brush cylinder 35 and saws into two streams, one of which, of greater intensity, flows between the baffle 15 and the brush cylinder, and for a portion of its travel follows the periphery of the brush cylinder, and the other of which, of 40 less intensity, flows downwardly through the passage 17 defined between the baffles 14 and 15 and passes rearwardly under the lower end of the baffle 15, thereafter merging with the stream which flows between the 45 upper end of said baffle 15 and the brush cylinder.

The heavier particles of trash or foreign matter pass downwardly through the passage 17, which passage is in substantial vertical alignment with the discharge space 16 between the lower ends of the baffles 13 and 14. The air stream flowing downwardly through the passage 17 does not have sufficient strength or intensity to carry the 50 heavier particles of trash rearwardly into the space above the baffle 13, and further, the momentum of the falling heavier particles of trash will prevent them from traveling rearwardly with the air current as it 55 escapes from the passage 17, for which reasons, the heavier particles of trash as they issue from the lower end of the passage 17 fall through the space 16 upon the floor of the linter casing.

60 In order to produce lint of substantial

commercial value, it is necessary that the lint should be free not only of the heavier particles of trash, but also of the lighter particles of trash. The heavier particles of trash are separated, as above explained, by 70 effecting their precipitation through the space 16 upon the floor of the linter casing. The lighter particles of trash, however, are carried over with the lint in the air currents which circulate above the baffle 13 and it 75 is for the purpose of separating the lighter particles of trash from the lint that the eddying or whirling air currents are principally employed in the present invention. The development of the eddying or whirling 80 air currents in the space above the baffle 14 is secured by a number of factors, among which may be mentioned the converging relation of the baffles 13 and 14, the preferably, though not necessarily, concave form 85 of the baffles 13 and 14, the arrangement of said baffle 13 whereby its upper end projects at an angle across the lower portion of the lower inlet end of the flue 11, the provision of transverse lips or flanges 18 at appropriate intervals on the baffle 13, and the provision of the baffle 15. The baffle 14, in the embodiment disclosed and now preferred, has an upper concave portion 14^a 90 which is formed to direct the air stream 95 flowing downwardly through the passage 17 into the space above the baffle 13 and a lower concave portion 14^b which is formed to co-operate with the baffle 13 in producing the above described whirling motion of the air 100 currents in the space above the baffle 13.

The lighter particles of trash separated from the lint above the baffle 13 are precipitated in a receptacle 19 which is preferably formed as a part of the baffle 13 and extends transversely across the linter casing. The baffle 13 includes in its make-up a screening panel 20 which is fitted in the mouth of the said receptacle and through which the fine trash passes into the receptacle. The receptacle 19 is provided with a hinged or otherwise displaceable bottom panel 21 which may be opened when desired to permit the contents of said receptacle to discharge therefrom upon the floor of the linter casing. The panel 21 is, however, normally closed to avoid interference with the development of the whirling air currents. The fine trash is heavier than the lint and, hence, tends to sink to the lower portion of 115 the space above the baffle 13. The air currents circulating above the baffle 13 comprise a stream principally made up of the air induced between the brush cylinder and the saws and which flows with substantial directness into the flue 11, and a second stream principally made up of the air entering the casing through the opening 8 and of the air circulating through the passage 17, such second stream circulating as an eddying or 120 125 130

whirling current immediately above the baffle 13 and under the stream which passes directly into the flue 11. The lint is carried in the upper strata of the air currents with 5 substantial directness into the flue 11. The fine trash which, as stated, tends to sink to the lower portion of the space above the baffle 13, is caught in the eddying or whirling air current and in the course of the end- 10 less circulation of said whirling air current or eddy, sinking lower all the while, ultimately passes through the screening panel 20 into the receptacle 19.

The air currents which pass into the flue 15 11 carry practically all the lint to the condenser and may carry a small, almost negligible percentage of fine trash, to effect the ultimate separation of which the arrangement shown in my said pending application 20 Serial No. 864,651 may be employed, such arrangement comprising a receptacle or trap 24 set into the lower wall of the flue 11 and extending from the inlet end of said flue, a screening panel 25 covering the mouth of 25 the receptacle 24, and transverse baffles 26 arranged at suitable intervals along the flue 11 and projecting upwardly across said flue, one of said baffles 26 being arranged midway of the flue, preferably above the panel 25, 30 and another one being arranged adjacent the condenser 12.

When the cotton reaches the condenser 12, it is practically absolutely free from trash and, hence, is of very superior quality. 35 The quantum of the cotton obtained is increased because not only is substantially all of the trash separated from the cotton, but conversely, substantially all of the cotton is separated from the trash.

40 In order to regulate the intensity of the draft through the flue 11, it is preferred to employ a baffle 22 which is arranged at the upper side of the inlet end of the flue 11 and has its rear portion formed as a lip 45 which projects somewhat into said flue, restricting the inlet area thereof. The baffle 22 is adjustable in a direction longitudinally of the machine; for this purpose, being formed with slots through which pass 50 the bolt or other fastenings 23 employed to secure the baffle 22 in position.

The several baffles referred to extend throughout the width of the casing 1 and are secured to the side walls of said casing 55 in any suitable manner. Preferably, the baffles have at their ends apertured attachment lugs 27 for the reception of suitable fastening screws. In the case of the baffle 13, the lugs 27 are slotted to provide for slight upward and downward adjustments of said baffle with a view to regulating the air current conditions in accordance with the character of the material treated and other exigencies of use. The baffle 13 preferably has at its upper end a transverse hook-

like flange 28 which engages over a transverse upward projection 29 provided at the lower end of the lower wall of the flue 11 in order that said baffle may be supported partly from said flue, whereby the assemblage and adjustment thereof in the linter casing will be greatly facilitated.

The seed separated by the grid 3 and escaping through the opening 10 falls into a receptacle 30 preferably provided for its 75 reception. A percentage of the seed will, however, escape through the bars of the grid 3 and the adjacent gin saws. Such escaping seed is ordinarily lost, there being no separation thereof from the precipitated 80 trash. One of the features of the present invention consists in the provision of a plate 31 which extends entirely across the casing from a point between the brush cylinder and the saws, forwardly and downwardly to 85 a point above the receptacle 30. Any seed which may escape through the grid 3 and between the saws will fall upon the plate 31 and will slide along said plate until it discharges from the lower end thereof into the 90 receptacle 30.

The invention is not limited to the exact details of construction shown, nor to the combination in one structure of all of its several features, and no specific description 95 herein contained is intended to impose any limitation upon the scope of the appended claims which does not inhere in the language thereof.

Having fully described my invention, I 100 claim:—

1. In a cotton seed linter, a casing having an outlet flue and having openings for the admission of air, means acting to induce an air current through said casing and into 105 said flue, means to clean cotton fiber from cotton seed whereby the separated fiber passes into said casing above and with said air current and a pair of baffles arranged under said respective means to provide a 110 vertical air passage in line with the air current which issues from between said means, the baffle nearest said flue being arranged to divide said air current into two streams, one of which carries lint and light motes 115 and flows over said baffle directly toward said flue and the other of which carries heavier motes and flows downwardly through said air passage and under said baffle toward said flue.

2. In a cotton seed linter, a casing having an outlet flue and having openings for the admission of air, means acting to induce an air current through said casing and into 120 said flue, means to clean cotton fiber from cotton seed whereby the separated fiber passes into said casing above and with said air current, a pair of baffles arranged under said respective means to provide a vertical air passage in line with the air current 125 130

- which issues from between said means, the baffle nearest said flue being arranged to divide said air current into two streams, one of which carries lint and light motes and flows over said baffle directly toward said flue, and the other of which carries heavier motes and flows downwardly through said air passage and under said baffle toward said flue, and a third baffle arranged adjacent the inlet of said flue and constructed to coact with said first-named baffles in developing a whirling air current between said passage and said flue, the light motes being caught in said whirling current and being precipitated by gravity in the course of the action of said current, the lower end of the third baffle being somewhat widely separated from the lower ends of the other baffles to provide a space alining with said passage through which heavier motes are precipitated in advance of said whirling air current.
3. In a cotton seed linter, a casing having an outlet flue and having openings for the admission of air, means acting to induce an air current through said casing and into said flue, means to clean cotton fiber from cotton seed whereby the separated fiber passes into said casing above and with said air current, a pair of baffles arranged under said respective means to provide a vertical air passage in line with the air current which issues from between said means, the baffle nearest said flue being arranged to divide said air current into two streams, one of which carries lint and light motes and flows over said baffle directly toward said flue, and the other of which carries heavier motes and flows downwardly through said air passage and under said baffle toward said flue, a third baffle arranged adjacent the inlet of said flue and constructed to coact with said first-named baffles in developing a whirling air current between said passage and said flue, the light motes being caught in said whirling current and being precipitated by gravity in the course of the action of said current, the lower end of the third baffle being somewhat widely separated from the lower ends of the other baffles to provide a space alining with said passage through which heavier motes are precipitated in advance of said whirling air current, and a receptacle set into said third baffle to receive the motes precipitated by said whirling air current and provided with a screening panel arranged in the plane of said baffle.
4. In a cotton seed linter, a casing having an outlet flue and having openings for the admission of air, means acting to induce an air current through said casing and into said flue, means to clean cotton fiber from cotton seed whereby the motes and separated fiber pass into said air current

and a system of coöperating baffles for developing from said air current a mote laden stream which has an initial downward travel and a subsequent whirling motion, the downward travel of said stream effecting the precipitation, by combined gravity and momentum, of the heavier motes and the whirling motion effecting the independent precipitation, by gravity, of the lighter motes.

5. In a cotton seed linter, a casing having an outlet flue and having openings for the admission of air, means acting to induce an air current through said casing and into said flue, means to clean cotton fiber from cotton seed whereby the motes and separated fiber pass into said air current, a system of coöperating baffles for developing from said air current a mote laden stream which has an initial downward travel and a subsequent whirling motion, the downward travel of said stream effecting the precipitation, by combined gravity and momentum, of the heavier motes and the whirling motion effecting the independent precipitation, by gravity, of the lighter motes, and a receptacle associated with one of said baffles to receive the precipitated lighter motes, said receptacle being provided with a screening cover.

6. In a cotton seed linter, a casing having an outlet flue and having openings for the admission of air, means acting to induce an air current through said casing and into said flue, means to clean cotton fiber from cotton seed whereby the motes and separated fiber pass into said air current, a baffle projecting inwardly and downwardly from the lower side of the inlet of said flue and provided with a mote receptacle and a screening cover for said receptacle and means, in coöperation with said baffle for developing from said air current a mote laden air stream which has an initial downward travel whereby to precipitate the heavier motes at a point in advance of said baffle and a subsequent travel over said baffle whereby to precipitate the lighter motes in said receptacle.

7. In a cotton seed linter, a casing having an outlet flue and having openings for the admission of air, means acting to induce an air current through said casing and into said flue, means to clean cotton fiber from cotton seed whereby the motes and separated fiber pass into said air current, and means for developing from said air current a stream laden with motes which has an initial downward travel whereby the heavier motes are precipitated by combined gravity and momentum and a subsequent travel toward said flue.

8. In a cotton seed linter, a casing having an outlet flue and having openings for the admission of air, gin saws for cleaning cotton fiber from cotton seed, a brush cyl-

- inder coacting with said gin saws and arranged intermediate the same and said flue and downwardly directed baffles terminating short of the bottom of the casing and providing a relatively narrow vertical passage for the continuous downward circulation of a mote laden air stream developed from the air current induced by said brush cylinder, whereby the heavier motes will be precipitated by combined gravity and momentum, said baffles being arranged, respectively, under said saws and under said brush cylinder.
9. In a cotton seed linter, a casing having an outlet flue and having openings for the admission of air, gin saws for cleaning cotton fiber from cotton seed, a brush cylinder coacting with said gin saws and arranged intermediate the same and said fiber, downwardly directed baffles terminating short of the bottom of the casing and providing a vertical passage for the downward circulation of the air current induced by said brush cylinder, said baffles being arranged, respectively, under said saws and under said brush cylinder, and the baffle under said brush cylinder being arranged to divide said air current into two streams, one of which passes downwardly through said vertical passage, and the other of which passes directly toward said flue and between said baffle and brush cylinder.
10. In a cotton seed linter, a casing having an outlet flue and having openings for the admission of air, gin saws for cleaning cotton fiber from cotton seed, a brush cylinder coacting with said gin saws and arranged intermediate the same and said flue, downwardly directed baffles terminating short of the bottom of the casing and providing a vertical passage for the downward circulation of the air current induced by said brush cylinder, said baffles being arranged, respectively, under said saws and under said brush cylinder, and a third baffle projecting inwardly and downwardly from the lower end of the flue and terminating above the bottom of the casing and at a distance from said first-named baffles, said third baffle being constructed to coact with the first-named baffles in developing a whirling motion in the air currents during their travel toward the flue.
11. In a cotton seed linter, a casing having an outlet flue and having openings for the admission of air, gin saws for cleaning cotton fiber from cotton seed, a brush cylinder coacting with said gin saws and arranged intermediate the same and said flue, downwardly directed baffles terminating short of the bottom of the casing and providing a vertical passage for the downward circulation of the air current induced by said brush cylinder, said baffles being arranged, respectively, under said saws and under said brush cylinder, the baffle under said brush cylinder being arranged to divide said air current into two streams, one of which passes downwardly through said vertical passage, and the other of which passes directly toward said flue and between said baffle and said brush cylinder, and a third baffle projecting inwardly and downwardly from the lower end of the flue and terminating above the bottom of the casing and at a distance from said first-named baffles, said third baffle being constructed to coact with the first-named baffles in developing a whirling motion in the air currents during their travel toward the flue, and a receptacle set into said third baffle.
12. In a cotton seed linter, a casing having an outlet flue and having openings for the admission of air, gin saws for cleaning cotton fiber from cotton seed, a brush cylinder coacting with said gin saws and arranged intermediate the same and said flue, downwardly directed baffles terminating short of the bottom of the casing and providing a vertical passage for the downward circulation of the air current induced by said brush cylinder, said baffles being arranged, respectively, under said saws and under said brush cylinder, a third baffle projecting inwardly and downwardly from the lower end of the flue and terminating above the bottom of the casing and at a distance from said first-named baffles, said third baffle being constructed to coact with the first-named baffles in developing a whirling motion in the air currents during their travel toward the flue, and a receptacle set into said third baffle and provided with a screening cover in the plane of said baffle.
13. In a cotton seed linter, a casing having an outlet flue and having openings for the admission of air, gin saws for cleaning cotton fiber from cotton seed, a brush cylinder coacting with said gin saws and arranged intermediate the same and said flue, downwardly directed baffles terminating short of the bottom of the casing and providing a vertical passage for the downward circulation of the air current induced by said brush cylinder, said baffles being arranged, respectively, under said saws and under said brush cylinder, the baffle under said brush cylinder being arranged to divide said air current into two streams, one of which passes downwardly through said vertical passage, and the other of which passes directly toward said flue and between said baffle and said brush cylinder, and a third baffle projecting inwardly and downwardly from the lower end of the flue and terminating above the bottom of the casing and at a distance from said first-named baffles, said third baffle being constructed to coact with the first-named baffles in developing a whirling motion in the air currents during their travel toward the flue, and a receptacle set into said third baffle.

and provided with a screening cover in the plane of said baffle.

14. In a cotton seed linter, the combination with gin saws for cleaning cotton fiber from cotton seed and means for developing a current of air which carries away the fiber separated by said saws, of an inclined imperforate plate arranged immediately below the peripheries of said saws upon which

10 any cotton seed which may escape between

the saws with the separated cotton fiber will fall and by which a separate discharge of such intercepted cotton seed is effected.

15 In testimony whereof I have hereunto set my hand in presence of two subscribing witnesses.
